SUPPORTING CLIP

Denison B. Hull, Winnetka, Ill., assignor to Denison B. Hull, doing business as Otarion, Chicago, Ill.

Application April 12, 1945, Serial No. 588,003

1 Claim. (Cl. 24—3)

1

This invention relates to an improved flexible supporting clip for a small wearable electronic hearing aid, whereby said instrument may be securely supported in a pocket of the wearer's garment.

It is an object of the invention to provide a clip construction having provision for adjusting the same with reference to its connection to the hearing aid or corresponding associated device, which is readily applicable to said device for use, and which adjustably supports the same in a desired pocket or other receptacle in a very secure fashion resistant to inadvertent loss.

Other more specific objects and advantages of the invention will be apparent to those skilled in the art upon a full understanding of the improved apparatus herein described.

In the drawings,

Fig. 1 is a view in front elevation illustrating the clip construction as applied to a well known type of electronic hearing aid;

Fig. 2 is a similar rear view of the clip in operative position, illustrating provisions for securing the clip on the device;

Fig. 3 is a top plan view of the structure shown in Fig. 1;

Fig. 4 is a view in side elevation; and

Fig. 5 is a front view illustrating the clip perse prior to formation thereof into final form.

In the drawings, I have illustrated and designated by the reference numeral 10, the plastic casing of a well known type of portable or wearable hearing aid device. This casing has a generally rectangular flattened section with rounded top and bottom corners and rounded top, bottom and side edges, as clearly illustrated in Figs. 3 and 4. An adjustable volume control element 11 projects laterally of the casing. The reference numeral 12 in general designates the clip of the present invention. This clip is initially stamped out of sheet metal of suitable resilience and temper, preferably a .03 carbon steel, into the shape illustrated in Fig. 5. So stamped, the clip comprises a central, vertically upstanding attaching member 13, the lower extremity of which merges with laterally extending arms 14. These arms merge with vertically extending portions 15 having lateral outward arm continuations 16 adapted to embrace the sides of the casing in the finished form of the clip. Outwardly offset and downwardly depending spring detent fingers 17 are provided at the outer extremities of the arm continuations 16, these fingers being offset or punched at the lower extremities thereof to provide friction nibs 18. The central member 13

likewise is conformed by offsetting to provide a lug 19 extending in the same direction as the nibs 18 in the initial condition of the clip blank.

In adapting the blank illustrated in Fig. 5 to its final form, the arm continuations 16 are conformed by a suitable die in curves corresponding generally to, but of somewhat smaller initial radius than, the curvature of the sides of case 10. This enables the conformed clip to be slipped or snapped over the casing, with detent fingers 17 disposed forwardly thereof and the nibs 18 in springable engagement with the front of said casing. In order to sustain the clip relative to the casing, the rear wall of the latter has an adapter fixture 20 secured thereto as by rivets 21, said adapter 20 being preferably countersunk in the rear casing wall so as to be flush with the surface of the latter. Said fixture is provided with one or more vertically spaced detent recesses 22 in which the forwardly projecting lug 19 is selectively receivable. Hence, in operative position the clip may be springably secured to the casing either in the position illustrated in Fig. 2 or in a more elevated position thereon, so that less of the casing is visible when inserted in a user's pocket with clips 17 engaging over the lip of the pocket in a well known fashion. Likewise, adjustability of the clip on the instrument adapts the same for optimum reception and support in pockets of varying depth. The multiple engagement afforded by the pair of spaced detent fingers 17 obviously increases the security of the retention of the hearing aid on the wearer's garment, effectively preventing inadvertent displacement therefrom.

Referring to Fig. 2, it will be noted that the laterally extending arms 14, being spaced substantially below the attaching lug 19, and integrally connected thereto by the member 13, exert a definite bracing and stabilizing action on the rear of the casing 10, resisting any tendency of the clip to cant should vertical thrust be exerted on the casing, and assisting the spring arms 16 to resist springing distortion from that cause. By reason of this feature, it is possible to employ a relatively short length of arm 16, thereby positioning the detent fingers 17 adjacent the curvature of the forward side edges, as clearly illustrated in Fig. 3. This enhances the effectiveness of the grip of nibs 18 on the wearer's garment, since the material of the latter is in effect snubbed around the curved edges between the casing and clip.

The device is simple and inexpensive and readily applied to and adjusted on the hearing aid,

Further advantages will readily suggest themselves.

I claim:

A clip of the type described, comprising a central, relatively flat attaching portion engageable with one side of a supported body over a substantial area and having a projecting attaching element thereon adapted for engagement in an aperture of the body, a pair of arms integrally connected to said central attaching portion in spaced relation to said element, said arms extending laterally in planar form a substantial distance from opposite sides of and in coplanar relation to said attaching portion, and arm extensions integrally connected to and generally paralleling said arms in offset relation thereto, said extensions being spaced from said arms to embrace the sides of a supported body and terminating in a pair of laterally spaced depending clips, said clips being spaced transversely from 20 said attaching portion, in opposed, facing rela-

tion to the latter, and being springably engageable with a support to hold the body in place thereon.

DENISON B. HULL.
